ABSTRACT OF THE DISCLOSURE

A garment hanger having outwardly extending arms and a cross bar connecting the outward extremities of the said arms, the said arms having a triangular wedge portion adjacent their extremities on the inner edges thereof, with the long side of the triangular wedge spaced from the cross bar, providing a space therebetween for gripping and removably retaining a garment.

This invention provides a garment hanger adapted for the hanging of two-piece suits, slacks, straps, and the like.

My invention provides a hanger having the usual shoulder supporting arms, a cross bar supporting portion and a hook portion for supporting the same.

Along the inner edges of the supporting arm portions 15 adjacent the outer ends thereof are triangular wedge members 16. The long side of the triangular wedge and the cross bar 17 are substantially parallel but spaced from each other and adapted to hold a pair of trousers or the like, therebetween.

The triangular wedge spaced from the conventional cross bar of a garment hanger precludes accidental removal of garments, precludes shifting of the garment from side to side, and eliminates any marking or undesirable creasing or mussing of the garment while being held.

In the case of trousers and ladies' slacks, especially those of rayon, Dacron, and other synthetics on the market today, this hanger is a great help since they slide easily off the usual hanger. Inserting trousers between the triangular wedge and the cross bar portion is faster and the garment can be easily inspected without disturbing it.

FIGURE 1 is a fragmentary elevational view showing the hanger, the triangular wedge and the cross bar portion.

2

FIGURE 2 is also a fragmentary elevational front view showing part of the structure of the hanger supporting a pair of trousers inserted between the triangular wedge and the cross bar portion of the hanger.

- 5 Referring now to the drawings, there is shown in FIGURE 1 part of a conventional garment hanger 13 formed from plastic or other suitable material which is employed for supporting garments 14 about the lower shoulder portion 15 there forming the triangular wedge 16 adjacent to the conventional cross bar 17 of a garment hanger 13.
- 10 10 In use the triangular wedge portion parallel to but spaced from the supporting cross bar portion of a garment hanger are adapted to hold in place a pair of trousers in a place provided for and the garment is supported for 15 transportation or storage in the manner shown in FIG. 2.
- 15 Quite obviously, while the invention has been described as capable of holding in place a pair of trousers, the hanger structure shown herein may be used for supporting other garments such as ladies' slacks and the like.
- 20 Having described the invention, I claim:
1. A garment hanger having a hanging hook, a pair of equal and laterally opposed continuous rigid shoulder supporting arms extending downwardly and outwardly from said hook, a rigid cross bar connecting the free ends 25 of said arms, each of said shoulder supporting arms having a flat solid and rigid immovable wedge member along the inner edge adjacent their outer ends, the long side of said wedge being closely spaced from but parallel to the cross bar portion of the hanger, the space being of a size to receive and removably hold a substantial portion 30 of the front and rear edges of the leg portions of a pair of trousers.
2. The garment hanger of claim 1 wherein the complete hanger is formed of a plastic material.
